HORATIO B. WEAVER, OF HARTFORD, CONNECTICUT.

Letters Patent No. 60,974, dated January 1, 1867.

IMPROVEMENTS IN LOCKS AND KEYS.

The Schedule referred to in these Letters Patent and making part of the same.

TO ALL WHOM IT MAY CONCERN:

Be it known that I, H. B. WEAVER, of Hartford, Hartford county, State of Connecticut, have invented an Improvement in Locks and Keys; and I do hereby declare the following to be a full, clear, and exact description of the same, reference being had to the accompanying drawing, and to the letters of reference marked thereon.

My invention consists of a lock and key, constructed and operating in the peculiar manner fully described hereafter, so that the door to which the lock is attached may be readily opened from the inside of the room by turning the handle of the lock, but so as to compel any one outside to insert a key of peculiar construction into the handle before the bolt can be drawn back by turning the said handle.

In order to enable others skilled in the art to make and use my invention, I will now proceed to describe its construction and operation. On reference to the accompanying drawing, which forms a part of this specification—

Figure 1 is a sectional view of my improved lock.

Figure 2, a transverse section, on the line 1 2, fig. 1.

Figures 3 and 4, face views of the lock, with the cover plate removed.

Figure 5 is a section of that handle of the lock which is outside the door; and

Figure 6, a section of the same, on the line 5 6, fig. 2.

Similar letters refer to similar parts throughout the several views.

A represents the casing of the lock, to which is fitted a cover-plate, *a*. A bolt, *B*, is arranged to slide in grooves, formed for its reception in the casing *A*, and, owing to a spiral spring, *b*, has a tendency to remain in the position shown in fig. 1. Adjacent to the bolt *B* is a plate, *C*, in which are formed projections fitting into corresponding grooves formed in the bolt, so that the plate *C* and bolt *B* may have a longitudinal movement independent of each other. Into an opening, *d*, in the bolt projects a lug, *e*, forming part of the bolt, a precisely similar opening, *d'* and projecting lug, *e'*, being formed in the plate *C*. There are two lock spindles, *D* and *D'*, and on the inner end of the spindle *D*, within the opening *d* of the bolt, are two projections, *f f*, the other end of the said spindle projecting through the cover-plate *a*, and being secured to a handle, *E*, which is intended to be on the inside of the door to which the lock is attached. The inner end of the spindle *D'* projects into and is arranged to turn in the inner end of the spindle *D*; and on this spindle *D'*, and within the opening *d'* of the plate *C*, are formed two projections, *f' f'*, similar to the projections *f f* of the spindle *D*. This spindle *D'* has a recess, *g*, of the form shown in the transverse sections, figs. 5 and 6, and is surrounded by the stem of the handle *E'*, the latter being attached to the casing *A* by means of a collar, *h*, and being arranged to turn freely around the spindle *D'*, excepting under the circumstances described hereafter. Within the recess of the spindle *D'* are pivoted three or more tumblers, *F*, of the bell-crank form, and hooked at one end, as shown in the drawing; and against one arm of each of these tumblers bears a spring, *i*, one end of which is secured to the spindle *D'*. By the action of these springs the ends of the arms *j* of the tumblers have a constant tendency to remain in a recess, *k*, cut in the plate *C*, fig. 1. On the inside of the case *A* is formed a straight bar or fence, *k'*, the edge of which is so located that the hooked ends of the tumblers will, when in the position shown in fig. 2, pass between the said fence *k'* and the plate *C*. In the handle *E'* is cut a slot, *l*, adapted to the reception of the key *G*; and on each side of the recess *g* of the spindle *D'* are formed grooves, *m*, for the reception of the legs of the key, the latter having wards, *n n n*, into which, when the key is introduced into the slot *l*, fit the arms *j'* of the tumbler-levers *F F F*. Two curved or inclined recesses, *p p*, are cut in the key, one on each edge of the same, for a purpose described hereafter. It will be seen that the bolt *B* may have a backward motion independent of the plate *C*, but that on account of the shoulder *b'*, fig. 1, of the bolt the plate *C* cannot be moved back without pushing the bolt with it. As the spindle *D* is secured to the handle *E*, it is only necessary to turn the latter in either direction in order to draw the bolt back, the inner end of the spindle *D* turning upon the projecting portion of the spindle *D'* without moving the latter, while one of the projections *f f* of the former acts directly upon the edge *x*, fig. 1, of the opening *d* in the bolt, forcing the same back along the grooves formed for its reception in the casing *A*. Until the key is inserted into the slot *l* of the handle *E'* the door is effectually locked to any one outside the room, it being impossible to move the bolt

B back by turning the handle E' without using the key, inasmuch as the turning of the spindle D' is prevented by the presence of the arms *j* of the tumblers in the recess *k* of the plate C. But if the key G be inserted into the opening *l*, and forced along the grooves *m m* into the recess *g* of the spindle D' until it assumes the position shown in fig. 6, and the handle be slightly turned until part of it enters one of the curved recesses, *p*, of the key, the latter will be held securely in its position, and the tumblers F will have been moved enough upon their pivots to lower the arms *j* from the recess *k* of the plate C, but will not have been forced down so far as to cause the hooked ends of the tumblers to lie below the edge of the fence *k'*. If the handle E' be now turned in either direction, the arms *j* of the tumblers will clear the sides of the recess *k*, and pass under the plate C, and will also clear and pass over the top of the fence *k'* in the manner shown in fig. 2, while one of the projections *f'* of the spindle D' will bear against the edge *y* of the opening *d'* in the plate C, and move the latter back, together with the latch-bolt B. It will be seen that, by the use of an improper key, one or more of the tumblers may be so placed as to hook over the edge of the fence *k'*, while the others may lie within the recess *k* of the plate C. Or the others may be in the proper position, and still the turning of the spindle D' be prevented by the hooking of the misplaced tumbler on the fence *k'*. Any desired number of tumblers may be used, the key having corresponding number of wards.

I claim as my invention, and desire to secure by Letters Patent—

1. The combination of the two spindles D and D', the bolt B, plate C, and the tumblers F, or their equivalents, the whole being constructed, arranged for joint operation, and applied to a lock-case, substantially as and for the purpose herein set forth.
2. The combination of the above and the fence *k'*, the whole being constructed, arranged, and operating as described.
3. The bell-crank tumbler-levers F, hung to the spindle D', and arranged in respect to the recess *k* of the plate C, substantially as described.
4. The tumblers F, arranged in respect to the slot *l*, in the stem of the handle E', as described.
5. The slot in the tubular stem of the handle E', in combination with notches *p*, in the edges of the key.

In testimony whereof I have signed my name to this specification in the presence of two subscribing witnesses.

HORATIO B. WEAVER.
